UNITED STATES PATENT OFFICE

2,573,619

ELECTRIC DISCHARGE DEVICE

David Lorimer Smart, Stafford, England, assignor
to The English Electric Company Limited, Lon-
don, England, a British company

Application October 20, 1949, Serial No. 122,462
In Great Britain October 27, 1948

10 Claims. (Cl. 313—163)

1

This invention relates to pool cathode electric discharge devices of the kind in which the envelope, at least in the region where the anode seal is made, is of vitreous material and which have a single main anode. It may also relate to similar multi-anode devices in which the anodes are mounted in the main body of the device and not in side arms.

In such devices considerable quantities of the cathode material are continually being vaporised by the action of the cathode spot, and this material will condense on any part of the device whose temperature is not maintained above a certain value, which depends on the pressure of the vapour. It is important that no appreciable quantity of cathode material should condense in parts of the device where gradual increments in the quantity of material so collected would eventually result in drops of the material falling on to the anode of the device, or intermittent spilling over of the material, giving rise to undesirable electrical characteristics.

According to the invention a pool cathode electric discharge device has an anode sealed through a re-entrant vitreous portion of its envelope and a tube surrounding said anode and clamped or sealed directly to said re-entrant portion, said tube being so shaped as to prevent the collection thereon of any appreciable quantity of liquid cathode material formed by condensation in the upper part of the device and so arranged as to ensure that such material returns to the cathode without penetrating the space between the tube and the anode. The tube may form part of a control grid and may consist of a substantially regular cylindrical metal tube attached to the re-entrant portion of the envelope by means of a metal clamp and in order that the spacing between the anode and the tube may be made sufficiently large to prevent a flash-over in the case of a rectifier, the re-entrant portion of the envelope may be bulged outwardly in the region where the tube is clamped to it. The anode stem may be sealed to a narrowed inner end of the re-entrant portion by means of an intermediate metal cup and a shield may be provided around this seal. In an alternative arrangement the end of the re-entrant portion to which the anode stem is sealed may be turned back upon itself, thus reducing the total length of the device. In either case the design of the device and its cooling arrangements, if any, must be such that no cathode material will condense on any portion of the envelope between the anode seal and the point where the tube is sealed or clamped to the envelope.

2

In order that the invention may be clearly understood several forms thereof will be described with reference to the accompanying drawings.

5 In Fig. 1, a tubular glass envelope 1 is provided with a re-entrant portion 2 having a narrow neck 3 to which an anode 4 is sealed by means of a metal cup 5. A grid tube 6 surrounds the anode 4 and its seal and is clamped by means of a metal clamp 7 on to the re-entrant portion 2 at an intermediate region 8 which is bulged outwardly to correspond with the internal diameter of the grid tube 6. In order to prevent damage to the glass near the seal, due to being hit by high speed vapour ions, a shield 9 is provided attached to the anode stem. The re-entrant portion 2 will attain a considerably higher temperature in operation than the remainder of the envelope 1 and, in the region between the grid tube 6 and the anode seal 5, condensation of cathode material will be substantially prevented. It is, however, desirable that condensation should take place in the upper portion of the envelope 1 in order that the general operating temperature of the device may be kept within reasonable limits. Any condensation, however, which takes place in the upper part of the envelope where the re-entrant portion is joined to it will have no opportunity of collecting in any considerable quantity on the grid tube 6.

10 In Fig. 2, an alternative form of the invention is shown in which corresponding parts have been given the same reference numerals as in Fig. 1. In this case, however, the inner end 3 of the re-entrant portion of the envelope and the cup 5 which is sealed thereto is inverted. By this means the anode seal is brought nearer to the upper end of the device and the anode 4 is thus also raised. This results in decreased length of the device.

15 In Figs. 3 and 4 are shown further constructions embodying the invention and here again the same reference numerals as were used in Fig. 1 have been used for corresponding parts. In Fig. 3 the re-entrant portion 2 has attached to it a depending metal ring 6a by means of a glass to metal seal and the grid tube 6 is fitted into the open end of the ring 6a.

20 A shield 9 at anode potential is included to reduce heat radiation from the anode to the glass in the region of the anode seal and to reduce the possibility of anode material being deposited on this glass.

25 Fig. 4 shows a somewhat similar arrangement but in this case the ring 6a is flanged at its open

end and a corresponding flange formed on the tube 6 is secured thereto for example by spot welding. A shield 9a in the form of an apertured metal disc is secured at the junction of the tube 6 and the ring 6a. The shield 9a is thus at grid potential.

Fig. 5 shows an arrangement for a multi-anode device in which the envelope 1 is provided as before with a re-entrant portion 2 having three narrow necks 3 to each of which an anode 4 is sealed by means of a metal cup 5. A grid tube 6 surrounds all the anodes 4 and is secured to the re-entrant portion 2 by means of a clamp 7. The anodes 4 are separated by radial baffle plates 10 and are provided with individual shields 9.

The anodes may be of graphite or may be in the form of hollow metal cups.

What I claim as my invention and desire to secure by Letters Patent is:

1. In a pool cathode electric discharge device including an envelope mainly of vitreous material, a tubular integral re-entrant portion on said envelope, an anode sealed through said re-entrant portion and a tube surrounding said anode supported directly on and forming with said re-entrant portion a seal impervious to liquid cathode material, the outer surface of said tube extending from said re-entrant portion always towards the cathode so as to prevent the collection thereon of any appreciable quantity of liquid cathode material.

2. The invention defined in claim 1, wherein said tube forms part of a control grid for the device.

3. The invention defined in claim 1, wherein said tube is substantially cylindrical throughout its length and is secured to said re-entrant portion by means of a constricting clamp.

4. In a pool cathode electric discharge device having an envelope mainly of vitreous material, a tubular integral re-entrant portion on said envelope, said portion being provided with a further narrower portion, an anode sealed through said narrower portion and a tube surrounding said anode supported directly on and forming with the wider re-entrant portion a seal impervious to liquid cathode material, the outer surface of said tube extending from said wider re-entrant por-

tion always towards the cathode so as to prevent the collection thereon of any appreciable quantity of liquid cathode material.

5. The invention defined in claim 4, wherein said tube forms part of a control grid for the device.

6. The invention defined in claim 4, wherein said tube is substantially cylindrical throughout its length and is secured to said re-entrant portion by means of a constricting clamp.

7. The invention defined in claim 4, wherein said narrower re-entrant portion is turned back within the wider re-entrant portion so that the anode seal is nearer the end of the device than the further projecting parts of the re-entrant portion.

8. In a pool cathode electric discharge device having an envelope mainly of vitreous material, a tubular integral re-entrant portion on said envelope, a plurality of anodes sealed through said re-entrant portion, a tube surrounding said anodes supported directly on and forming with said re-entrant portion a seal impervious to liquid cathode material and baffles within said tube separating said anodes, the outer surface of said tube extending from said re-entrant portion always towards the cathode so as to prevent the collection thereon of any appreciable quantity of liquid cathode material.

9. The invention defined in claim 8, wherein said tube forms part of a control grid for the device.

10. The invention defined in claim 8, wherein said tube is substantially cylindrical throughout its length and is secured to said re-entrant portion by means of a constricting clamp.

DAVID LORIMER SMART.
